FIG. 4.

UNITED STATES PATENT OFFICE.

WESLEY VAN NETTE, OF POPLAR, OHIO.

MUSICAL INSTRUMENT.

SPECIFICATION forming part of Letters Patent No. 694,589, dated March 4, 1902.

Application filed December 1, 1900. Serial No. 38,298. (No model.)

To all whom it may concern:

Be it known that I, WESLEY VAN NETTE, a citizen of the United States, and a resident of Poplar, Crawford county, State of Ohio, 5 have invented a new and useful Musical Instrument, of which the following is a specification, reference being had to the accompanying drawings, forming part thereof.

My invention relates to improvements in 10 musical instruments of the stringed variety, in which a series of pickers for the strings are arranged to be operated from a keyboard which is fingered or manipulated like that of the ordinary piano.

15 In this class of instruments, the principal difficulty found to exist in the successful use of a picker to set the strings in vibration, instead of a hammer as in the piano, is the necessity of returning the picker, after having been operated to pick or snap the string, to its initial or starting position without again touching said string, as, in the latter event, the vibration of the string would be impeded and the harmony of sound destroyed.

20 It has, therefore, been the principal object of my invention to provide a simple and effective means for properly controlling the movement of the pickers whereby possibility of their striking against the strings when being 25 returned to their starting position after snapping or picking the same as referred to is prevented.

30 A further object of my invention is to improve the general construction and operation 35 of the several parts forming an instrument of this character, so as to render the same more effective and desirable for the purposes intended.

35 In carrying my invention into effect, I provide a casing of suitable design in which is 40 located a harp-shaped stringed instrument which I term a "harp," a keyboard of usual arrangement as in the ordinary piano, a series of pickers arranged to be operated from 45 said keyboard to pick or snap the strings and produce any desired harmony of sound, and a damping mechanism for the strings, the whole forming what may properly be termed a "piano-harp."

50 The novel construction and combination of parts embodying my invention will be herein-

after set forth in detail and pointed out in the claims.

In the accompanying drawing: Fig. 1 is a 55 plan view of an instrument embodying my invention, with certain of the parts removed and broken away, and with the top removed from the case, which latter is that of the ordinary grand piano. Fig. 1^a is an enlarged 60 vertical cross-section of the action case taken through line 1^a—1^a of Fig. 1. Fig. 2 is an enlarged plan view of certain of the parts broken away, showing the relative arrangement of the strings, pickers, keys, and a portion of the damping mechanism. Figs. 3 and 65 4 are enlarged detail views illustrating the movement of the pickers relative to the strings. Fig. 5 is a plan view of the harp and a part of its adjusting mechanism removed from the case. Fig. 6 is a detail view showing 70 the connection between the foot pedals and certain parts of the harp and damper adjusting and operating mechanisms, and Fig. 7 is a detail view to be hereinafter referred to.

To explain in detail: 1 indicates the outer 75 or main case within which the several parts of the instrument are contained and supported. This case may be of any suitable design and construction, but the same as indicated in the drawings is like that of the ordinary 80 grand piano. A harp, comprising a sounding board 2 with strings 3 stretched over the same, is supported within the lower part of this case 1, while at the front of the latter and in position above the harp is located the 85 action case which carries the keyboard, pickers, dampers, and other operating parts of the instrument. This action case, which consists of the end pieces 4, 4, united by a number of connecting rails and boards, has a 90 hinged connection at its rear end with a part of the case 1, in a manner as will hereinafter be described, whereby it may be swung upward so as to render the several parts carried thereby, and also the harp, easily accessible 95 for the purpose of repairing, adjusting, or otherwise manipulating the same.

The strings 3 of the harp are picked, in accordance with my invention, by means of a series of pickers 6, each of which is carried 100 by a hinged or pivoted block 5 which has connection with the keys 7 through the medium

of a rod 8 to be operated thereby in a manner as will hereinafter be described.

Each of the blocks 5, in the present instance shown, is pivotally supported by a pivot pin 9 between the projecting ends of two plates 10, 10, secured on the opposite sides of a bar 11. This bar 11, which I term the picker-block bar, is pivoted at its rear end upon a rod 12 between two ears 13, 13, whereby its front end with the supported picker-block 5 may be capable of a vertical movement. A coiled spring 14, connecting at one end with a pin 15 on the bar 11 and at its opposite end with a pin 16 on the upper end of the block 5, acts to yieldingly hold the latter in a normal stationary position relative to said bar by holding an upper extension 5' of the block in contact with the front cushioned end of a block 17 which is secured on the bar 11, as clearly shown in Figs. 1^a and 3. A second coiled spring 18, connecting at one end with a pin 19 secured in the action case and at its opposite end with a pin 20 on the bar 11, acts to yieldingly hold the latter and the connected picker-block 5 in a normal raised position with the picker 6 above the string 3.

On the rear side of the block 5 is secured an arm 21 which rests, when the block is in its said normal raised position, upon the raised front end of a spring arm 22, which latter is attached at its rear end to a strip 23 on the under side of a cross rail 24. Said spring arm 22 is provided with a vertically disposed bend or offset 25 therein at a point adjacent to its front end forming a catch and guide which is adapted to engage with the end of the arm 21 at a certain time in the operation of the parts and control the movement of the block 5 and its supported picker 6, in a manner as will be described.

In the operation of the instrument, the operator, in depressing one of the keys 7 from its normal raised position, as indicated in Fig. 3, thereby lowers the bar 11 and its connected block 5 through the medium of the rod 8 until the said bar comes in contact with the upper cushioned surface of the rail 24, as indicated by dotted lines in Fig. 3 and by full lines in Fig. 4. The picker 6 has now reached a position in front of the string 3, as indicated by dotted lines in Fig. 3, and, upon the continued downward pressure of the key, the block 5 is caused to rock or swing on its now stationary pivot 9 and move the picker 6 across the string 3 as indicated in Fig. 4 and pick or snap the same. During such time as the block 5 is being depressed from the position indicated in full lines in Fig. 3 to that shown in dotted lines, the spring arm 22 yields downward under the pressure of the engaging arm or projection 21 of said block as indicated by dotted lines in said Fig. 3. When the block is rocked on its pivot, however, the end of the arm 21 is swung backward off the front raised portion of the spring arm 22 and thereby allows the latter to spring upward

with its catch portion 25 engaging the said arm 21, as shown in Fig. 4. When the operator now releases the key and the latter is raised with the connecting parts, the end of the arm 21 on the block 5 rides up behind the vertical catch portion 25 of the spring arm 22 and thereby causes the picker 6 to be held back and away from engagement with the string 3 until it reaches a position above the same, at which time the end of the arm 21 rises from engagement with the catch portion 25 and permits the lower end of the block to be rocked forward under the action of the spring 14 to return the picker to its initial position forward of the string. In this manner the movement of the block 5 is so controlled that the return of the picker to its initial or starting position, after having been operated to snap the string, is effected without liability of its touching or striking against the latter.

In order to allow for the free movement of the key 7 and block 5, which parts swing in different arcs, the connecting rod 8 is provided with an enlarged head 8' at each end thereof, as most clearly shown in Figs. 3 and 4, one of which loosely engages with the inner side of a plate 27 on the under side of the key 7 through an opening therein, and the other loosely engages with the inner side of a spring plate 28 on the block 5 through a slot or opening therein. Such form of connection insures the free action of the connected parts, but any other suitable means of connection other than that shown and described might be employed without departure from the invention.

The keys 7 are held in a normal raised position with their top surface in engagement with the lower cushioned edge of the "name-board" 29 by means of coiled springs 30, which latter, as clearly shown in Fig. 1^a, are seated within a supporting rail 31 with their upper end bearing against the under side of the keys. A cushioned rail 31' located beneath the keys 7 receive the contact of the latter when depressed.

The picker-block bars 11 are each held against lateral displacement and guided in their up and down movements by means of plates 32, 32, which are supported upon the rail 24 and extend upwardly between each of the said bars, as clearly shown in Figs. 1^a and 2. In order to permit these bars 11 being readily removed from and placed into position for the purpose of adjusting or repairing any of the parts carried thereby, I have slotted their rear ends, as at 11' in Fig. 1^a, whereby they may be readily slipped on or off their pivot supporting rod 12, the same being removably held on the latter by means of the springs 18. As a means to prevent any undue noise or rattle of the block 5 on its pivot pin 9 at the forward end of the bar 11, I have seated a spring 33 between the parts which acts to hold the block in contact with its pivot

and prevent undue movement or rattle of the same thereon.

The pickers 6, which may be formed of spring brass, steel, or other suitable material, 5 are each secured in adjustable position at the lower end of its supporting block 5 by means of a suitable clamp, which latter, as herein shown, comprises a band 34 which embraces the said picker 6 and an extension 5" of the block 5 and is provided with a clamping screw 35 for securing the picker in adjustable clamped position. These pickers are each inclosed in a fold of felt or similar material 36 for the purpose of deadening any sound 15 of the same after snapping the strings. The inclosing felt also permitting any movement or adjustment of the pickers without contact with their holding or supporting parts.

The damper mechanism for each of the 20 strings is as follows: A bell-crank lever 37 is pivotally connected with a bracket 38 on the rail 24 and is arranged with one arm extending into engagement with a cushion on the under side of the picker-block carrying 25 bar 11, and its other arm having connection, through the medium of a string, wire, or other flexible connection 40, with the vertical arm of a second bell-crank lever 41, which latter is pivotally connected with a bracket 42 on a 30 rail 43 and has connection at the end of its horizontal arm with a vertically sliding frame 44 which operates through openings in the rail 43 and carries a damper pad 45 at its lower end for contact with the string, as clearly 35 shown in Fig. 1^a. In the operation of the instrument, when a key is depressed, the picker-block bar 11 in being lowered thereby acts upon the engaging lever 37 and rocks the same on its pivot, which action of said lever 40 causes the second lever 41 to be also rocked on its pivot through the medium of the connection 40 and thereby raise the damper-pad 45 from contact with the string. The damper-pad is held in such raised position by the bar 45 until the picker has been operated to snap the string, after which, as the key is released and the said bar 11 returned to its normal raised position, the damper-pad is permitted to again drop into contact with the string 50 and damp the same. As a means for adjusting the vertical position of the damper-pad relative to the string, I have provided the lever 41 with an adjusting-key 46 with which one end of the string 40 is connected. By 55 turning this key in the proper direction to shorten or lengthen the said string, the position of the lever 41 will of course be adjusted to raise or lower the damper-pad.

The rail 43 with which the dampers are 60 connected is attached to the forward ends of two bars 43', 43'', which have a hinged connection at their rear end with the action case at 43'', as clearly shown in Fig. 1^a. The rail 43 with its supporting end pieces thus form a 65 single hinged frame which may be operated by any suitable means to raise and lower all

of the dampers in unison and independent of the action of the keys. The means as herein shown for controlling the movement of the said damper rail 43 is as follows: A rocker-shaft 47 is journaled at its opposite ends in the action case frame and provided with two arms 47', 47'', which extend at their front end beneath the rail 43 and are provided with antifriction rolls 48 for engagement therewith, as most clearly shown in Figs. 1^a and 6. A third arm 49 of this shaft 47 is connected through the medium of a pitman rod 50 with a foot-pedal 51, from which latter the operator may rock the shaft 47 to effect the raising 80 and lowering of the rail 43 and connected dampers, as desired. As a means to adjust the rail 43 with its connected dampers in a lateral direction relative to the strings, I have attached said rail to its end supports 43', 43'', by screws 77, 77, and provided the same with elongated slots 78, 78, therein (see Fig. 6) through which the said fastening screws extend.

The main or outer casing 1 is provided with 90 two castings 53, 53, seated and made fast therein adjacent to its opposite ends, as shown in Fig. 1. These castings, as most clearly shown in detail in Fig. 7, are each formed with a ledge 54 on which is supported 95 a horizontally adjustable block 55 to which the action case is pivotally connected by means of a pivot screw or bolt 56. At its forward end the said action case is supported in vertical position by means of two screws 57, 100 57, which are carried in lugs 58, 58, on the ends 4, 4, of the action case with their lower ends resting upon a supporting surface 59 of the castings 53, 53. By turning these screws 57 in the proper direction, the vertical position 105 of the action case may be adjusted as desired.

A horizontal or backward and forward adjustment of the blocks 55, 55, with the supported action case is permitted by means of 110 horizontally elongated slots 60, 60, in said blocks through which the fastening bolts 61 extend. A lateral adjustment of the action case may also be secured by means of its supporting pivot screws 56, 56, which may be adjusted to draw the action case back and forth in such direction. These several adjustments of the action case are provided for in order that the pickers carried thereby may be adjusted to their proper position relative to the 115 strings on the harp.

A further adjustment of the pickers relative to the strings is secured by the block 17 on the bars 11 which forms the stop against which the picker-blocks 5 are held by the 125 springs 14. By adjusting the position of these stop-blocks 17 back and forth on the bars 11, the picker-blocks may be caused to assume a position with the pickers at a greater or less distance from the strings, as will be 130 obvious. Adjustment of these stop-blocks 17 is permitted by means of the elongated open-

ings therein, indicated by dotted lines in the drawings, through which the fastening or clamping screws 17' extend.

The harp, according to my invention, comprises the sounding board 2 having a light metal frame or band 2' (which is preferably formed of steel) fitted around its outer edge with a flange or extension 2" thereof projecting over its upper surface, as clearly shown in Fig. 1^a. Secured upon the said flange portion 2" of this steel frame are the tuning keys 3' for the strings, which keys, as herein shown, are the same as the so-called "patented" keys ordinarily used on guitars and similar instruments. The bridges 3" over which the strings are stretched are located upon the sounding board adjacent to the said flange 2" of the frame 2'. A harp constructed in the manner as thus described can be made very light, as the steel frame provides sufficient strength to carry the strain of the strings, thereby allowing the sounding board to be made very light, and furthermore, the steel frame and steel strings being connected are effected alike under varying weather conditions, thereby preventing the strings from readily getting out of tune.

The harp has a hinged or pivotal connection at its rear side with the main case at 63, and adjacent to its front side and at opposite ends thereof is provided with two plates 64, 64, attached thereto which are engaged by supporting and adjusting screws or eccentrics 65, 65, which latter are each mounted in a rotatable but vertically stationary position in an extension 66 of the castings 53, 53, as most clearly shown in Fig. 7. The screws or eccentrics 65, 65, are provided with rigidly connected lever arms 67, 67, which are united by a pivotally connected rod 68. By moving this rod laterally or in a longitudinal direction the screws or eccentrics 65, 65, will thereby be caused to receive a partial turn and so raise or lower the harp relative to the pickers whereby the strings may be snapped to produce any desired forte or pianissimo, it being understood that the pickers will engage the strings with more or less pressure or force according to the relative positions of the same.

In order to obtain the proper variation of sound as the harp is raised or lowered, it is necessary that the left or bass end should be moved to a greater degree than the other or treble end. To provide for such difference in movement, the lever arm 67 at the bass end is shorter than the other so that its movement when operated by the rod 68 will be greater and so give its connected screw or eccentric a correspondingly greater turn to increase the vertical movement of such end of the harp accordingly.

The rod 68 may be operated from foot-pedals to raise or lower the harp as desired by any suitable means, the means as herein shown being as follows: Two pivoted levers 70, 70, connected with pedals 71, 71, through

the medium of rods 72, 72, are arranged with one end in position to engage with a pin 73 on the rod 68, which latter is yieldingly held in a normal central position by means of two pivoted levers 74, 74, which engage with the opposite sides of the rear end of the pin 73 and are connected at their free ends with coiled springs 75, 75, which are attached to a part of the main case 1. By such arrangement and combination of parts, when the operator presses upon one of the pedals, the end of the connected lever 70 is moved into engagement with the pin 73 and forces the rod 68 laterally in one direction and against the pressure of the opposite spring 75 to thereby either raise or lower the harp. When the operator thereafter removes his foot from the pedal, the said opposite spring which has been put under tension acts to automatically return the rod 68 and connecting parts to their normal position.

Having thus forth a practical embodiment of my invention, I do not wish to be understood as confining myself to the particular details of construction and combinations of parts as illustrated and described, as the same may be more or less materially modified without departure from the spirit of my invention.

What I claim, and desire to secure by Letters Patent, is—

1. In a musical instrument of the class described, the combination, with the keyboard and strings, of a series of pivoted blocks carrying pickers for the strings, movable supports for said blocks, means forming an operative connection between the blocks and the key-board independent of the block supports, and means for controlling the movement of the blocks and preventing contact of the pickers with the strings during their return movement after having been operated to snap the latter, for the purpose set forth.

2. In a musical instrument of the class described, the combination, with the keyboard and strings, of a series of pivoted vertically movable blocks carrying pickers for the strings, movable supports for said blocks, means forming an operative connection between the blocks and the key board independent of the block supports, and means for controlling the movement of the blocks and preventing contact of the pickers with the strings during their return movement after having been operated to snap the latter, for the purpose set forth.

3. In a musical instrument of the class described, the combination, with the key-board and strings, of a series of pivoted bars yieldingly held in a normal stationary position, a series of pickers pivotally supported by said bars and having operative connection with the keys to be operated thereby, means for limiting the downward movement of said bars prior to the engagement of the pickers with the strings, and means for controlling

the movement of the pickers and preventing contact of the same with the strings when being returned to their initial position, for the purpose set forth.

5 4. In a musical instrument of the class described, the combination, with the keyboard and strings, of a series of pivoted bars yieldingly held in a normal stationary position, a series of blocks carrying pickers pivotally supported by said bars and having operative connection with the keys to be operated thereby, means for limiting the downward movement of said bars prior to the engagement of the pickers with the strings, and means for controlling the movement of the pickers and preventing contact of the same with the strings when being returned to their initial position, for the purpose set forth.

10 5. In a musical instrument of the class described, the combination, with the keyboard and strings, of a series of pivoted bars yieldingly held in a normal stationary position, a series of blocks carrying pickers pivotally supported by said bars and arranged to be operated from the keyboard, means for yieldingly holding said blocks in a normal stationary position relative to their supporting bars, means for limiting the downward movement of the bars prior to the engagement of the pickers with the strings, and means for controlling the movement of the pickers and preventing contact of the same with the strings when being returned to their initial position, for the purpose set forth.

15 6. In a musical instrument of the class described, the combination, with the keyboard and strings, of a series of pivoted bars yieldingly held in a normal stationary position and having removable connection with their pivot support, a series of blocks carrying pickers pivotally supported by said bars and arranged to be operated from the keyboard, means for limiting the downward movement of the bars prior to the engagement of the pickers with the strings, and means for controlling the movement of the pickers and preventing contact of the same with the strings when being returned to their initial position, for the purpose set forth.

20 7. In a musical instrument of the class described, the combination, with the keyboard and strings, of a series of pivoted bars yieldingly held in a normal stationary position, a series of blocks carrying pickers pivotally supported by said bars and arranged to be operated from said keyboard, an antirattle spring seated between said blocks and their supporting bars, means for limiting the downward movement of the bars prior to the engagement of the pickers with the strings, and means for controlling the movement of the pickers and preventing contact of the same with the strings when being returned to their initial position, for the purpose set forth.

25 8. In a musical instrument of the class described, the combination, with the keyboard

and strings, of a series of pivoted bars yieldingly held in a normal stationary position and having removable connection with their pivot support, a spring for removably holding said bars in connection with their pivot support, a series of blocks carrying pickers pivotally supported by said bars and arranged to be operated from the keyboard, and means for controlling the movement of the pickers, substantially as and for the purpose set forth.

30 9. In a musical instrument of the class described, the combination, with the keyboard and strings, of a series of pivoted bars movably held in a normal stationary position, a series of blocks carrying pickers pivotally supported by said bars and having operative connection with the keys to be operated thereby, means for controlling the movement of the pickers, and means for adjusting the position of the blocks relative to their supporting bars and thereby the position of the pickers relative to the strings, for the purpose set forth.

35 10. In a musical instrument of the class described, the combination, with the keyboard and strings, of a series of pivoted bars movably held in a normal stationary position, a series of blocks carrying pickers pivotally supported by said bars and having operative connection with the keys to be operated thereby, adjustable stop-blocks located on said bars, means for yieldingly holding said picker-blocks in contact with said stop-blocks, and means for controlling the movement of the pickers, substantially as and for the purpose set forth.

40 11. In a musical instrument of the class described, the combination, with the key-board and strings, of a series of blocks provided with pickers having operative connection with the key-board to be operated thereby, movable supports to which the picker blocks are pivoted, and means for engaging with the picker blocks or a part thereof when moved in one direction, retaining such engagement and guiding the same relative to the strings during their return movement, and subsequently disengaging therefrom, substantially as and for the purpose set forth.

45 12. In a musical instrument of the class described, the combination, with the keyboard and strings, of a series of vertically movable pivoted blocks carrying pickers for the strings and arranged to be operated from the said keyboard, and a movable arm having a catch projection for engaging with said blocks or a part thereof when moved in one direction and guiding the same during their return movement past the strings, for the purpose set forth.

50 13. In a musical instrument of the class described, the combination, with the keyboard and strings, of a series of vertically movable pivoted blocks carrying pickers for the strings and arranged to be operated from the said keyboard, and a spring arm having a catch projection for engaging with said blocks or

a part thereof when moved in one direction and guiding the same in their return movement, for the purpose set forth.

14. In a musical instrument of the class described, the combination, with the keyboard and strings, of a series of vertically movable bars, a series of blocks provided with pickers supported by said bars and having operative connection with the keys, and a damper

150 mechanism, comprising a series of damper pads, and a series of levers having an operative connection with the latter and arranged to be operated by said picker-block supporting bars, for the purpose set forth.

15. In a musical instrument of the class described, the combination, with the keyboard and strings, of a series of vertically movable bars, a series of blocks provided with pickers supported by said bars and having operative

20 connection with the keys, and a damper mechanism, comprising a series of damper pads, a series of levers operated by said picker-block supporting bars, means, including a flexible cord or wire, forming an operative

25 connection between said levers and damper pads, and means for adjusting the length of said cord, for the purpose set forth.

16. In a musical instrument of the class described, the combination, with the keyboard,

30 strings, and means operated from the keyboard for engaging with said strings, of a damper mechanism for the strings, comprising a movable rail, a series of frames supported to slide in said rail and provided with attached

35 damper pads, means forming an operative connection between said damper pad frames and the keyboard, and means for moving said rail with the connected dampers, for the purpose set forth.

40 17. In a musical instrument of the class described, the combination, with the keyboard, strings, and means operated from the keyboard for engaging with said strings, of a damper mechanism for the strings, comprising a

45 hinged rail or support, a series of frames supported to slide in said rail and provided with attached damper pads, means forming an operative connection between said sliding damper-pad frames and the keyboard, and a pedal

50 having connected means for raising and lowering said rail with the connected dampers, for the purpose set forth.

18. In a musical instrument of the class described, the combination, with the main case, 55 of an action case having a hinged connection adjacent to its rear end with said main case, and means for adjusting the vertical position of the action case relative to the main case, for the purpose set forth.

60 19. In a musical instrument of the class described, the combination, with the main case having contained therein a stringed instrument comprising a sounding board with strings stretched thereover, of an action case

65 provided with a keyboard and a series of pickers supported in said main case, and means

for adjusting the vertical position of said action case with its supported parts relative to the said stringed instrument in the main case, for the purpose set forth.

70 20. In a musical instrument of the class described, the combination, with the main case having contained therein a stringed instrument comprising a sounding board with strings stretched thereover, of an action case 75 provided with a keyboard and a series of pickers supported in said main case, and means for securing a backward and forward adjustment of said action case with its supported parts relative to the main case and the 80 stringed instrument therein, for the purpose set forth.

21. In a musical instrument, the combination, of the main case, two plates or castings connected with said case and provided with 85 horizontally adjustable blocks connected therewith, and an action case having a hinged connection adjacent to its rear end with said adjustable blocks and supported in a vertically movable position at its front end upon 90 said plates or castings, substantially as and for the purpose set forth.

22. In a musical instrument, the combination, of the main case, two plates or castings connected with said case and provided with 95 horizontally adjustable blocks connected therewith, and an action case having a hinged connection adjacent to its rear end with said adjustable blocks and adjacent to its front end provided with adjusting screws or pins 100 resting upon stationary supports, for the purpose set forth.

23. In a musical instrument, the combination, with the main case, and an action case supported by the latter provided with a key- 105 board and a series of string engaging devices arranged to be operated from said keyboard, of a stringed instrument, comprising a sounding board with strings stretched thereover, supported in the main case below the action 110 case, screws engaging with said stringed instrument, and means for operating said screws to raise and lower the stringed instrument relative to the string engaging devices, for the purpose set forth.

115 24. In a musical instrument, the combination, with the main case, and an action case supported by the latter provided with a key- 120 board and a series of string engaging devices arranged to be operated from said keyboard, of a stringed instrument, comprising a sounding board with strings stretched thereover, having a hinged connection at its rear end with the main case, screws engaging with said stringed instrument at its front end to support and vertically adjust the same, and means for operating said screws for the purpose set forth.

125 25. In a musical instrument, the combination, with the main case, and an action case 130 supported by the latter provided with a key- board and a series of string engaging devices

arranged to be operated from said keyboard, of a stringed instrument, comprising a sounding board with strings stretched thereover, having a hinged connection at its rear end with the main case, screws engaging with said stringed instrument at its front end to raise and lower the same, each of said screws being provided with a lever-arm, one of which

is shorter than the other, a rod connecting said lever arms, and means for operating said rod, for the purpose set forth.

WESLEY VAN NETTE.
